UNITED STATES PATENT OFFICE.

PETER J. McNERNEY, OF OAKLAND, CALIFORNIA, ASSIGNOR TO SOUVENIR NOVELTY COMPANY, OF SACRAMENTO, CALIFORNIA, A CORPORATION OF CALIFORNIA.

DESIGN FOR A CLOCK-CASE.

43,544.

Specification for Design.

Patented Feb. 11, 1913.

Application filed July 22, 1912. Serial No. 710,992. Term of patent 3½ years.

To all whom it may concern:

Be it known that I, PETER J. McNERNEY, a citizen of the United States, residing at Oakland, in the county of Alameda and State of California, have invented a new, original, and ornamental Design for a Clock-Case, of which the following is a specification, reference being had to the accompanying drawings, forming part thereof.

The figure is a plan view of the clock case showing my new design, the body of the clock case being formed of unfinished redwood provided with corner pieces constituting small squares and having a contrasting grain, the center of the large redwood square having a dial surrounded by a blue border.

I claim—

The ornamental design for a clock case, as shown and described.

In testimony whereof I affix my signature in presence of two witnesses.

PETER J. McNERNEY.
